UNITED STATES PATENT OFFICE

116,277

DESIGN FOR AN AIRCRAFT LANDING WHEEL POSITION INDICATOR

Paul F. Bechberger, West Hempstead, N. Y., as-
signor to Bendix Aviation Corporation, South
Bend, Ind., a corporation of Delaware

Application January 12, 1939, Serial No. 82,317

Term of patent 14 years

To all whom it may concern:

Be it known that I, Paul F. Bechberger, a citizen of the United States, residing at West Hempstead, State of New York, have invented a new, original, and ornamental Design for an Aircraft Landing Wheel Position Indicator, of which the following is a specification, reference being had to the accompanying drawing, forming part thereof.

In the drawing:

Fig. 1 is a front elevational view of an aircraft

landing wheel position indicator, showing my new design; and

Fig. 2 is a side view of the device as illustrated in Fig. 1.

The characteristic features of the design reside in the portions shown in full lines in the drawing.

I claim:

The ornamental design for an aircraft landing wheel position indicator, as shown and described.

PAUL F. BECHBERGER.
